FIG. 1

FIG. 4

FIG. 2

FIG. 3

FIG. 1 is a front elevational view of an illuminable window decoration embodying my new design.

FIG. 2 is a rear elevational view thereof.

FIG. 3 is an end elevational view thereof.

FIG. 4 is a side elevational view thereof.

The drawing is lined to show the colors, red, yellow, blue and green.

The essential features of the design reside in the portions shown in solid lines; a conventional electric plug and cord being shown in broken lines.

I claim:

The ornamental design for an illuminable window decoration, as shown and described.
